TOY-BIRD

Ihei Okamoto, 28 Yamanouchi-cho, Seikanji,
Higashiyama-ku, Kyoto, Japan

Filed Jan. 11, 1961, Ser. No. 63,521

Term of patent 14 years

(Cl. D34—2)

FIG. 1 is a front view of a toy-bird showing my new design;

FIG. 2 is a back view of FIG. 1;

FIG. 3 is a plan view of FIG. 2;

FIG. 4 is a bottom view of FIG. 1; and

FIG. 5 is right side view of FIG. 2.

The left side view of the toy-bird is symmetrical with the disclosure of FIG. 5.

I claim:

The ornamental design for a toy-bird, as shown and described.
